(57) **CLAIM**

The ornamental design for a serving stand, as shown and described.

DESCRIPTION

FIG. 1 is a front perspective view of a serving stand showing my new design;

FIG. 2 is a front elevational view;

FIG. 3 is a right side view;

FIG. 4 is a rear elevational view;

FIG. 5 is a top plan view thereof; and,

FIG. 6 is a bottom plan view.

The broken lines are for illustrative purposes only and form no part of the claimed design.
